Continuation of application Serial No. 651,930,
January 16, 1933, now Patent 2,015,895, dated
October 1, 1935. This application August 19,
1935, Serial No. 36,872

5 Claims. (Cl. 81—103)

My invention relates to wrenches in general, the particular embodiment herein disclosed being incorporated in pipe wrenches. This application is a continuation of my application Serial No. 651,930, filed January 16, 1933, now issued as Patent No. 2,015,895, Oct. 1, 1935.

It is an object of my invention to provide a mechanism to hold the movable jaw of a wrench in any selected position, in which mechanism is incorporated means optionally operable to lock the first mechanism positively in jaw securing position, but which locking means, upon movement to unlocked position, will not move the jaw securing mechanism from jaw-secured position. 10 A further object is to provide mechanism of the type mentioned which can be conveniently and compactly incorporated in the body of wrenches having the general proportions of those now in use, and which will not project from the wrench body in a manner to interfere with the customary use of the wrench.

The principal object of my invention is to provide a mechanism having the above mentioned characteristics which is operable for quick adjustment of the movable jaw to a position spaced at any desired distance from the fixed jaw. More specifically it is my purpose to eliminate the tedious adjusting operation associated with the conventional screw-operated adjusting means.

It is an object to provide such operation by employing a spring forcing the movable jaw away from the fixed jaw, which upon release of the securing mechanism will force the movable jaw outward to its full extent. The movable jaw may then be moved inward any desired amount, to be automatically held in such position. It may also be positively locked in that position by a single locking member.

It is also an object to provide means having the general characteristics mentioned, which shall be rugged and not likely to be damaged by normal use of the wrench, reliable in operation, and simple to construct and assemble.

Still another object obtained by my invention as embodied in pipe wrenches is the provision of improved means normally urging the movable jaw to the position of nearest approach to the fixed jaw, or in an alternative form, to a position intermediate the position of nearest approach and the farthest distant position, which means are incorporated in the body of the wrench and replace the usual exposed leaf springs.

It is also an object, in conjunction with a pipe wrench, to construct the same in such manner that the very considerable stresses developed in

use can be relieved from the pivot about which the movable jaw swings, and delivered directly from the movable jaw or its immediate support to the handle.

Other objects, and in particular those resulting from the mechanical details of my device, may be ascertained from the specification with reference to the accompanying drawings, the novel features of which are defined by the claims appended to the specification.

My invention includes the novel parts and in particular the arrangement and formation of such parts, shown in the drawings and described in the specification, the novel features of which are pointed out in the claims.

Preferred embodiments of my invention are illustrated in the drawings.

Figure 1 is a side elevation of my invention incorporated in a pipe wrench, parts being shown in position about to grasp a pipe.

Figure 2 is a sectional elevation of the same wrench with parts locked in position ready to grasp a pipe, and Figure 3 is a similar view with parts in the movable jaw releasing position.

Figure 4 is a transverse section through the same wrench, substantially on the line 4—4 of Figure 2.

Figure 5 is a side elevation, and Figure 6 is an elevation partly in section, showing a slightly modified form of the pipe wrench.

In the pipe wrenches illustrated a fixed jaw 1 is formed on or secured to a handle 10, and a movable jaw 2 is formed on or secured to a slide 20, which moves within a guide 12 formed in the saddle 5. Within the saddle cavity is located an upstanding pin 11, surrounded by a compression spring 21 which bears against the inner side of the saddle end, and extends into a bore 22 in the slide 20 of the movable jaw. This spring always tends to force the slide out of the saddle cavity, and the movable jaw away from the fixed jaw, which movement is limited by a stop pin 23 engaging the end of a slot 15 within which it slides.

When the movable jaw 2 is forced inward against the action of the spring 21 it is normally held from being forced outward again under the influence of this spring by engagement of transverse serrations on the wedge block 3', with similar serrations formed on the back of the slide 20. This wedge block 3' is preferably, though not necessarily, cylindrical in shape, and is guided for movement towards and from the slide 20 in a chamber 14 formed in the saddle and opening at an angle into the guide 12. Thus disposed, one

surface of this chamber faces away from the movable jaw 2, so that a wedging action is effected upon the wedge block 3' between the slide and this surface as the slide tends to move outward 5 under the influence of the spring 21. It may be seen that while the interengaging serrations or corrugations on the wedge and slide may not be necessary, they are desirable to eliminate all possibility of slippage under the separating pressure 10 exerted when the wrench engages and operates upon the work.

To insure further the secure and constant wedging engagement of the wedge block with the slide, whether the wrench is in use or not and in 15 whatever attitude the wrench may be held, a spring 30' is employed interengaged between a recess in the end of the wedge block and the end of the wedge chamber or a screw such as 36 which forms the end of the wedge chamber, but which is 20 removable for disassembly of the wedge and its associated parts from the body of the saddle.

When the wrench is to be used at a fixed setting for some little time it may be desirable to eliminate the quick adjustable feature inherent in 25 the spring-pressed wedge block. Ordinarily the wedge block will be moved with a ratchet action upon inward movement of the movable jaw by the workman. Such ratcheting action may be prevented by actuation of positive locking mechanism which includes a knurled jaw-locking member 4', rotatable about a pivot 40 journaled transversely in the wrench saddle. The knurled periphery of the member 4' projects from the rear surface of the saddle in a position for ready engagement by the thumb of an operator's hand holding the wrench. Upon the inner circumferential portion of the member 4' is formed a cam surface 42' which, upon turning of the member 4', will engage a rear portion of the wedge block 40 3', such as the shoulder formed by the notch 37. When the jaw-locking member is thus turned, the wedge block is held securely against the slide 20, and the wedge block cannot be moved therefrom by pressure, either accidental or intentional, upon 45 the movable jaw. This position of the parts is shown in Figure 2, and it will be evident that the ratcheting action above mentioned, which is permitted when the parts are in the positions shown in Figure 1, will now be prevented. As 50 long as the member 4' is turned to the position of Figure 2, therefore, the slide will be positively locked to maintain the movable jaw and the fixed jaw in the relative adjusted positions assumed when this member is turned to locking position.

55 It will be noted that the locking member 4' is disposed in the rear edge of the saddle, not in a side face thereof, and in this position does not project where it is likely to be engaged with the work and accidentally released. Furthermore, it 60 will be noted that the exterior contour of the saddle and the locking member 4' is the same, whether such member be in the locked or unlocked position. Still, whenever adjustment of the wrench is required, a finger may release the 65 locking member, and the movable jaw may then be pressed inward to a new adjusted position, or the wedge block may be withdrawn from the slide 20, as will be described, to release the jaw 2 for outward movement under the influence of the 70 spring 21.

75 It is to be particularly noted, however, that movement of the jaw-locking member 4' from locked to unlocked position, namely, from the position shown in Figure 2 to that shown in Figure 1, does not in the least disturb the position of

the wedge block 3'. This block still remains in slide-engaged position, and just as effectively maintains the fixed jaw in its adjusted position when the member 4' is in the position of Figure 1 as when it is in the position of Figure 2. The only difference is that inward adjustment of the jaw 2 may be accomplished at the option of the workman with the parts in the position of Figure 1, whereas such adjustment is impossible when the member 4' is turned to the position of Figure 2. In both cases, however, the movable jaw is held in definitely fixed relation to the fixed jaw by the action of the two springs 21 and 30' tending to force the wedge block 3' into the angle between and in engagement with the back 15 of the slide 20 and the inclined surface of the saddle cavity 14.

When it is desired to adjust the movable jaw to a position spaced farther away from the fixed jaw, it is necessary to withdraw the wedge block 3' from engagement with the slide preparatory to such movement. This operation may be accomplished by any type of member engageable with the wedge block 3' to move it away from the slide in opposition to action of the spring 30'. I have found it convenient to combine the wedge block releasing member with the locking member 4', and in the embodiment shown, such releasing member takes the form of the additional point 43, received in the slot 37 in the side of the wedge block. Thus the point 43 is engageable with an end of the slot 37, upon movement of the locking member 4' in a direction opposite to that required to lock the wedging member, and upon further movement thereof pressure of the point 43 will 35 move the wedge block axially to the position shown in Figure 3 where it no longer engages the slide 20. Thereupon the spring 21 acting on the slide 20 will force the movable jaw 2 outward to its limiting position, further movement thereof 40 being prevented by the stop pin 23, as explained heretofore. Thus the locking member here performs the dual function either of locking the parts in an adjusted position or releasing the wedge block from engagement with the jaw slide 45 to permit the movable jaw to slide to the extreme outer limit of its movement.

While in pipe wrenches of the type illustrated in the drawings the saddle 5 is pivotally supported at 51 from the handle 1, and therefore is not 50 directly connected to the fixed jaw 1, it is, to all intents and purposes, a part of the head of the wrench, even though it is a part which is pivotally supported with respect to the handle of the wrench. It will be noted that in the full open 55 position of the movable jaw the pin 23 is directly over the axis of the pivot 51, whereby the rocking movement of the movable jaw relative to the handle 10 is not disturbed.

It is desirable, in wrenches of this type, to provide spring means to hold the jaws swung somewhat away from their position of farthest approach (usually to the position of nearest approach), in order the more easily to close down upon a pipe. The means which I have provided 65 for this purpose are valuable in connection with this particular type of jaw adjusting and locking means, and are valuable also in conjunction with any type of pipe wrench. For this purpose I provide in the handle 10 a slot 16 extending substantially longitudinally of the handle (but not in line with the pivot 51), and in this slot is received a block 6. By means of a pin 60, or any like means, this block is connected to a depending ear 50 of the saddle 5, the pin 60 passing through 70

a transverse slot 56 in the ear 50 to limit relative movement of the saddle and the handle. The slot 56 is arranged at an angle less than a right angle to a line joining the axes of the pivot pin 51 and the stop pin 60. Consequently the action of a small spring 61 on the lock 6 in effect causes the pin 60, working within the slot 56, to slide to the position farthest distant from the pivot pin 51, or into the position shown in Figure 3, where 5 the movable jaw 2 has been swung about the pivot 51 to the position of closest approach to the fixed jaw 1, engagement of the saddle and jaw 1 limiting this movement. To engage the wrench with a pipe it is a simple matter to 10 press the end of the saddle 5 or of the slide 20 with the thumb, and thus to swing the wrench open into the position shown in Figure 2, but upon release, the spring 61 again urges the jaws to swing towards each other.

15 In some wrenches means are provided for swinging the movable jaw somewhat away from the position of closest approach, and of maintaining it in a position intermediate that of closest approach of the two jaws and farthest separation of such jaws. I have provided means 20 whereby this result can be accomplished in the modification shown in Figures 5 and 6. In this form the slot 56', corresponding to the slot 56 and receiving the ends of the pin 60, has two wrenches; that is to say, its opposite ends are disposed at an angle to each other, and each of them is at an angle less than 90° to a line joining the axes of the pins 60 and 51. When parts 25 are in the position shown in Figure 6, the spring 61 tends to urge the pin along the slot 56' to a position farthest distant from the pin 51, and it would be urged towards the same position if the pin 60 were in the opposite end of the slot 56'. The result is that parts tend to remain in an 30 intermediate position, as shown in Figure 5, with the jaws partly swung open.

In this form (as indeed I might in the preceding form) I have shown the block 6 as so proportioned, relative to its slot 16, and relative 45 to the slot 56', that upon swinging of the movable jaw into the position of closest approach to the fixed jaw, the block 6 bears at the end of its slot 16, and serves, through the pin 60 rather than through the pin 51 to take the longitudinal 50 stresses. Further to strengthen the wrench, in this form as well as in the form just previously described, the pivot ear 52 of the saddle is so formed that it bears snugly against the projecting rear side of the fixed jaw 1, and this engagement, when the parts are in the operative position of Figure 6, is such that the bearing at 53 serves as a fulcrum, thus relieving the pin 51 of that duty to a large extent, and considerably strengthening the wrench.

60 It will be observed further that there is no looseness of the slide 20 relative to the saddle 5, and all strains tending to bend the slide are resisted by the long bearing of the same within the saddle, even in the most extended position 65 of parts, as shown in Figures 3 and 6. By the arrangement shown and described, the wrench may be made lighter in weight than wrenches of corresponding type and size now in use, partly because of the elimination of large nuts and the like, and partly because of the fact that the parts may be more closely fitted in place, and thereby made to support each other better, though of lighter material.

What I claim as my invention is:

1. In a wrench, a handle having associated therewith a fixed jaw, a saddle pivotally mounted adjacent said fixed jaw and including a guide generally parallel to the handle and ears disposed one at each side of the handle, a slide received in said guide and carrying a movable jaw, means engageable with said slide to secure the same in any adjusted position, and a spring-pressed member extending transversely through an aperture in the handle, the handle aperture being 10 larger than the member, and said member having its ends engaged one in each saddle ear, and reacting from the handle to swing the saddle relatively thereto.

2. In a wrench, an apertured handle having 15 associated therewith a fixed jaw, a saddle pivotally supported adjacent the fixed jaw for limited movement and including a guide generally parallel to the handle and ears disposed one at each side of the handle, a slide received in said jaw 20 and carrying a movable jaw, means engageable between the saddle and slide to position the movable jaw at any selected spacing relative to the fixed jaw, a pin extending transversely through the handle aperture and engaging said saddle 25 ears, and spring means disposed within the handle aperture and reacting between said handle and said pin to control relative pivotal movement of the handle and saddle.

3. In a wrench, a handle carrying a fixed jaw, 30 a saddle pivotally supported adjacent the fixed jaw, and when swung to its position of closest approach to the fixed jaw bearing against the latter as a fulcrum, said saddle including a guide generally parallel to the handle, a slide received 35 in said guide and carrying a movable jaw, means engageable between the saddle and slide to position the movable jaw at any selected spacing from the fixed jaw, said handle having a slot disposed in the direction of its length, a block 40 slidable in such slot, and engageable by said saddle to slide as the saddle swings, and the block, its slot and the interengagement with the saddle being so proportioned that, upon swinging of the movable jaw to its position of closest 45 approach to the fixed jaw, the block bears at the end of its slot to take the longitudinal stresses.

4. In a wrench, a handle carrying a fixed jaw, a saddle pivotally supported adjacent the fixed 50 jaw, and when swung to its position of closest approach to the fixed jaw bearing against the latter as a fulcrum, said saddle including a guide generally parallel to the handle, a slide received in said guide and carrying a movable jaw, means engageable between the saddle and slide to position the movable jaw at any selected spacing from the fixed jaw, said handle having a slot disposed in the direction of its length, a block 55 slidable in such slot, and engageable by said saddle to slide as the saddle swings, and spring means associated with the block to swing the movable jaw away from its position of closest 60 approach to the fixed jaw.

5. In a wrench, a handle having associated therewith a fixed jaw, a saddle pivotally connected 65 to said handle and including a guide generally parallel to the handle, the pivot connection including a pivot pin, and a stop pin movable relative to both the saddle and the handle and adapted to limit their relative pivotal movement, and 70 a slide received in said guide and carrying a movable jaw.

LARS E. HAGBO.
